United States Patent

Des. 236,962
Patented Sept. 30, 1975

236,962

CLOCK FACE

Marion K. Summers, W. Commerce St.,
Brownstown, Ind. 47223

Filed July 18, 1973, Ser. No. 380,159

Term of patent 14 years

Int. Cl. D10—01

U.S. Cl. D10—125

FIG. 2

FIG. 1

FIG. 1 is a front elevational view of a clock face, showing my new design; and

FIG. 2 is a top plan view thereof.

The rear, not shown, is substantially plain and unornamented while the bottom and both sides are substantially similar to FIG. 2.

I claim:

The ornamental design for a clock face, substantially as shown and described.
